Filed July 11, 1962, Ser. No. 209,133
5 Claims. (Cl. 62—367)

This invention relates to means for producing cracked ice. More particularly, it relates to an ice freezing tray adapted to be used with conventional ice cube partition structures, and suitable for commercial or home freezers.

The many advantages of a supply of cracked ice are well known. With particular reference to domestic uses, it is often desirable to provide fragmented or cracked ice for use in beverages or in the serving of chilled foods. Equipment for providing cracked ice is not suitable for normal home use. It is customary to obtain such cracked ice by separately cracking cubes of ice after they are removed from the standard home freezer tray. Such methods, as are well known, are not convenient or fast.

One expedient is the dividing unit for trays as disclosed in the patent to Pappas, No. 2,799,998, July 23, 1957. The present invention may be considered an improvement on this earlier structure, for reasons set forth in the body of the specification.

It is an object of this invention to provide means to obtain cracked ice by simultaneously cracking each cube of ice in a partitioned tray.

It is another object of this invention to provide an ice freezing tray equipped with cracking means, and adapted to contain a conventional movable tray partition.

It is yet another object of this invention to provide an ice cube tray and partition combination in which said partition is of a conventional movable type, in which ice cubes frozen in said tray may be all simultaneously cracked by moving said partition.

Other aims and objects of this invention are made apparent in the specification.

The invention is best understood in connection with the drawings, in which like reference numerals refer to like parts and in which:

FIGURE 1 is a top view of a ice cube freezing tray and movable partition; and

FIGURE 2 is a view, partially in cross-section, taken along line 2—2 of FIGURE 1; and

FIGURE 3 is a view as in FIGURE 2 wherein the movable partition has been actuated to free and crack the ice; and

FIGURE 4 is a detailed view of a post means mounted in a tray.

The ice cube freezer tray and partition combination is generally designated 10. It includes the tray 20 and the partition 30. While many such combinations are known in which the partitions are stationary, it is necessary for the practice of this invention that the partition means 30 be of the movable type. The structure and operation of such movable partitions are well known, and in this invention are completely conventional.

The partition means generally includes a fixed longitudinal partition 36, adapted to run the length of tray 20 and conform to the appropriate inner dimensions of said tray, as best shown in FIGURE 2. A plurality of transverse blades 39 are provided, each of said blades 39 being dimensioned to fit inside said tray 20 as best shown in FIGURE 1.

A movable longitudinal partition 37 is provided, directly above the fixed partition 36, adjacent thereto and in sliding contact therewith. As best shown in FIGURES 2 and 3, the movable partition 37 is shorter than the length of tray 20. At one end thereof, the movable partition is connected to actuating means.

2

The actuating means include several elements, and its purpose is to move the movable partition 37 with relation to the fixed partition 36. The actuating means includes a lever 31 connected to the fixed longitudinal partition at lever pivot 33. In the particular form illustrated, the fixed partition extends upwards above its normal height at one end thereof, so that the lever 31 may be more easily pivoted thereto. An arm 35 is connected at one end thereof to lever 31 by means of arm pivot 32. Arm pivot 32 is positioned on said lever 31 a short distance from that end of the lever which has lever pivot 33. The other end of arm 35 is connected to an end of said movable longitudinal partition 37 by means of partition pivot 34 which is provided at one end of said partition. The foregoing elements comprise the actuating means.

Notches are provided in the upper edge of the movable partition 37 and in the lower edge of fixed partition 36. Each said set of notches corresponds with a transverse blade 39. Each blade 39 is continued through the notch 20 in the fixed partition and through the notch in the movable partition. Thus, each transverse blade 39 is provided with a vertical slot stopping short of the edges thereof, and through which the fixed and movable partitions fit.

In the normal or freezing position, the lever 31 lies flat, 25 and the blades are slanted, as shown in FIGURE 2. After the water or other material has been frozen, the lever 31 is raised, as shown in FIGURE 3. This operation moves the movable partition 37 to the left, and carries the top of each transverse blade 39 in the same direction. Thus, each transverse blade tends to pivot around its lower edge in its notch in the fixed partition. This operation in the conventional tray and partition combination, frees the ice cubes so that they may be easily removed.

It is understood that the ice shapes called cubes are not necessarily geometrically cubical, but are described as cubes in common usage. Also, it is apparent that the conventional partitions described above may vary from the form shown. For example, there may be a plurality of longitudinal partitions in the assembly.

The partition means 30 is useful in conjunction with a tray, generally designated 20. The tray 20 is generally and usually a shallow, elongated container open at the top. The tray comprises a bottom 22. At spaced intervals along the bottom 22 are provided a plurality of posts 24. Each such post 24 is a firm, preferably solid, upstanding member which rises from bottom 22 a substantial proportion of the depth of tray 20. Preferably, the post does not extend above the upper rim of the tray.

It is apparent from the drawings that a post 24 is provided to correspond to each ice cube compartment and defined by the longitudinal or partition, the transverse blades, and the sides, ends, and the bottom 22 of the tray. The ice cube compartment may be bounded by various combinations of some or all of the aforementioned members. Preferably, each post 24 is centered in its compartment.

A preferred form of the post is that shown in detail in FIGURE 4. In this embodiment a tapered post 24A is provided. It is firmly fastened to tray bottom 22 by means of a stud 24B extending through hole 22A in bottom 22. The stud is headed with head 24C. This is really one convenient way of fastening the post to the bottom, and other fastening means are within the scope of this invention.

In operation, a tray and partition means combination 65 are filled with water and the water is frozen. Lever 31, when operated upwards, frees the ice cubes as has been described, and simultaneously at least part of each cube is displaced laterally with respect to the fixed post extending in its compartment. The necessity of such movement 70 stemming from operation of lever 31 is apparent from comparing FIGURES 2 and 3. It has been found that

when this operation is performed, each cube of ice fragments or shatters or cracks into smaller irregular pieces, which have advantages as have been described.

This invention has several advantages over known similar structures. For example, only one post is required for each ice cube. It is a much easier and more economical operation to mount posts on the flat open surface of a tray 20 than to mount them on parts or faces of the partition means. In this invention therefore, the partition faces may be described as smooth. It has been found that the post mounted as set forth herein produces a more complete fragmentation of the ice with less effort than previously known means.

Another advantage is that it is possible to replace presently used trays with properly sized trays equipped with posts 24. It is a relatively simple matter to modify the simple shapes of standard sized ice cube trays by providing the post, whereas it would be extremely difficult to modify the various types of known partition means to be included with standard trays.

It is noted that a characteristic of this invention as opposed to other known ice breaker devices is that in this invention a post is held stationary and the ice to be broken is moved past it.

The scope of this invention to be determined by the appendant claims. The specification and drawings are illustrative and not limiting.

I claim:

1. An ice cube tray and partition combination, comprising a movable partition means having smooth faces, a tray, said partition means fitting into said tray and defining, together with said tray, a plurality of ice cube compartments, a plurality of rigid non-yielding posts mounted on said tray, each of said posts extending into one of said ice cube compartments, and actuating means attached to said partition means to move it.

2. An ice cube tray and partition means combination

set forth in claim 1 wherein said movable partition means comprises a longitudinal partition, and a plurality of transverse blades connected to said longitudinal partition.

3. An ice cube tray and partition means combination as set forth in claim 2 wherein said longitudinal partition comprises a fixed longitudinal partition and a movable longitudinal partition, and said actuating means is pivoted on said fixed longitudinal partition and operatively connected to said movable longitudinal partition by means of a pivoted arm.

4. An ice cube tray and partition means combination as set forth in claim 3 wherein each of said posts is mounted on the bottom of said tray in the interior thereof at approximately the center of each said defined ice cube compartment.

5. An ice cube tray and partition combination comprising a tray having a bottom, a rigid non-yielding metal post inside said tray affixed to the bottom thereof, partition means at least partially defining an ice cube compartment around said post, said partition means being movable, and having smooth faces and actuating means to move said partition, whereby ice formed in said compartment is moved relative to said fixed and stationary post when said actuating means is operated.
